(57) **CLAIM**

The ornamental design for a candle tower, as shown and described.

DESCRIPTION

FIG. 1 is a right side isometric view of a candle tower showing my new design;

FIG. 2 is a front view of a candle tower showing my new design;

FIG. 3 is a left side view of a candle tower showing my new design;

FIG. 4 is a right side view of a candle tower showing my new design;

FIG. 5 is a bottom view of a candle tower showing my new design;

FIG. 6 is a top view of a candle tower showing my new design; and,

FIG. 7 is a left side isometric view of a candle tower showing my new design.

The broken lines showing in the drawings are for the purpose of illustrating portions of the candle tower and form no part of the claimed design.

1 Claim, 6 Drawing Sheets
